UNITED STATES PATENT OFFICE

MICHEL TCHOURBITCH, OF PARIS, FRANCE, ASSIGNOR TO SOCIETE NOUVELLE DE CONSTRUCTIONS TELEPHONIQUES, OF PARIS, FRANCE, A CORPORATION OF FRANCE

AUTOMATIC TELEPHONE SYSTEM

Application filed January 24, 1931, Serial No. 511,041, and in France January 31, 1930.

It is frequently necessary, in telephony, to serve a certain number of small groups each of which comprises a certain number of subscribers which must be able to be connected up either to each other, or to the subscribers of one of the other groups, each group being, however, too small to justify a telephonic operator being constantly on duty at the exchange.

10 The course which has obviously been resorted to is to employ automatic telephony, and in particular the system which consists in joining up the groups to a town of a certain size where attendants are constantly on duty, 15 the automatic mechanisms which carry out the operations necessary at the group exchanges, or rural exchanges, being worked from a distance by the attendants at the town exchange, which is called the manual exchange.

Fig. 1 shows by way of example a system constituted in this way, the subscribers AB being connected up directly, either to the exchanges C R, or to the manual exchange M A. 25 The rural exchanges C R are connected up to the manual exchange M A either directly, like the exchanges CR₁, CR'₁, CR''₁, or through the medium of other rural exchanges; for example CR₃ is connected up to 30 M A through the medium of CR₂ and CR₁.

It is obvious that, in this arrangement, the apparatus at the rural exchanges cannot be permanently supervised and, moreover, it is advantageous to constitute them from the simplest parts possible, that is to say from relays, avoiding movable parts such as rotary selectors for example. These rural exchanges have, therefore, been constructed as relay exchanges, but those which exist have two disadvantages, namely there is generally only a single line connecting two rural exchanges with each other or connecting one of them to the manual exchange. Now practice has shown that this is insufficient for normal working. On the other hand, two serially related lines, for example CR₃, CR₂ and CR₂, CR₁ have been connected to each other by the aid of translators which produced a notable weakening of the currents.

35 The present invention relates to a system

of automatic telephony, particularly an automatic rural exchange fitted solely with relays which permits any number of lines to be used, (which lines will be termed herein-after "trunk lines") in order to connect two exchanges and connecting these lines to each other directly at the intermediate exchanges so that there shall never be more than a single translator in circuit, which will be located at the final exchange to which the calling or 55 called subscriber is connected.

For example, if the subscriber AB₂₇ at the exchange CR₄ is in communication with the manual exchange, the only translator in circuit will be at CR₄, the connections of the 60 lines made at CR₃, CR₂ and CR₁ being direct and purely metallic connections.

Hereinafter, we shall describe by way of example, the exchange CR₁, the others being fitted in an identical manner and we shall 70 designate by LO₁, LO₂, LO₃ the lines which connect this exchange to the manual exchange which may be called main trunk lines and by LO₁₄ and LO₁₅ the lines connecting it to CR₂ which may be called secondary trunk 75 lines.

The rural exchange is constituted according to the following general principle, which will be better understood by reference to the diagrammatic Figure 3 relating to CR₁.

The main trunk lines leading towards the manual exchange (that is to say LO₁, LO₂, LO₃ from CR₁, or LO₁₄, LO₁₅ from CR₂) are divided at the exchange under consideration by translators. The secondary trunk lines 80 LO₁₄ leading towards the more remote rural exchanges cross these lines LO₁, LO₂ . . . at the part situated between the translators and the manual exchange. The subscribers' lines (LA) of the rural exchange under consideration cross them, on the contrary, at the part farthest from the manual exchange relatively to the translators.

The rural exchange thus constitutes diagrammatically a Swiss commutator (—) 85 and the parts of this exchange which have the effect of producing the connections between the lines which cross each other, play the part of the plugs in a Swiss commutator. 90 100

This arrangement shows that connections between a line LO_1 , LO_2 . . . etc. and a line LA will be made through the medium of a translator while a connection between the lines LO_1 , LO_2 and the lines LO_{14} , LO_{15} will be made directly.

The connections which are made in a Swiss commutator by the introduction of the plugs connecting two bars are made here through the medium of different relays. There is also a line in each exchange called a local line, denoted by LL in Fig. 3, which crosses to the subscribers' lines and the lines such as LO_{14} which lead outwards from the exchange. This line serves to establish communication between two subscribers of the same exchange, 23 and 24 for example, or between a subscriber (24 for example) at CR_1 and a subscriber (26 for example) at CR_2 . In this latter case at the exchange CR_1 , the subscriber 24 is connected to LL , while at CR_2 the subscriber 26 is connected to LO_{14} , which is connected at CR_1 to LL . At this latter, that is CR_2 , also communication will be made through the medium of a single translator that of CR_2 .

The following description and the accompanying drawings show by way of example one mode of carrying out the present invention.

The Figures 4 to 13 are really part of a single drawing and could have been numbered $4a$, $4b$, etc. . . ., they have been numbered 4 to 13 for more clearness.

Fig. 1 is, as above stated, a diagrammatic example of the rural network which can be served, despite its complexity, by the new system.

Figs. 2 and 3 show diagrammatically, as above stated, the general arrangement of the incoming circuits, the outgoing circuits and the circuits of the rural subscribers at rural automatic exchange. Fig. 3 also shows the way in which Figs. 4, 5, 6 and 7 are assembled.

Fig. 4 shows the part IV of Fig. 3.

Fig. 5 shows the part V of Fig. 3.

Fig. 6 shows the part VI of Fig. 3.

Fig. 7 shows the part VII of Fig. 3.

Figs. 8, 9 and 10 show one of the selectors individual to the trunk line.

Fig. 11 shows the calling line finder, or selector.

Fig. 12 shows a cabinet interpolated in one of the trunk lines leading from the manual exchange to the first of the rural automatic exchanges.

Fig. 13 shows the essential parts provided at the manual exchange for working the rural automatic exchanges of the system.

Figs. 14 to 18 are simplified theoretical diagrams which permit of the way in which the various operations take place to be more easily followed.

In Figs. 4 to 12 which show in a detailed manner the way in which a rural exchange is

constructed, certain circuit connecting wires have been indicated by roman figures and by arabic figures within a circle in the drawings (thus, for example, the reference VIII (3) placed in front of a bracket embracing one or several ends of conductors indicated by the number within a circle, means that these conductors must be connected to the conductors bearing the number 3 within a circle in Figure 8).

In the new system, each subscriber's individual equipment (Figure 6) placed at the rural exchange, is constituted by a calling relay D which acts when the subscriber operates his magneto and serves to put the other parts into operation; by a local communication relay A which serves to put the subscriber into communication with a local line for conversations between subscribers of the same office; and by as many communication relays C as there are main trunk lines LO leading to the manual exchange MA . Each of these relays serve to put the subscriber into communication with the corresponding line. Each subscribers' station (not shown) comprises, in the case under consideration here, a line condenser and a calling magneto.

The trunk lines LO , which extend towards the manually operated exchange and which are organized in such a way that each one of them can be occupied by only a single station at one time, comprise a test or guarding relay J , which is operated when the line is occupied by a rural exchange subscriber, a conversation relay K , which serves in particular to operate the supervision signal at the manual exchange, a calling relay L , which serves to light up the calling lamp at the manual exchange (Figs. 6 and 7) and as many groups of relays M and N (M_1 , N_1 , M'_1 , M_2 , N_2 , M'_2 , N'_2 , etc. . . .) as there are lines like LO_{14} leading from the rural exchange under consideration to the next rural exchanges (Figs. 4 and 5) these relays serving to connect the corresponding lines to each other directly and to prevent the line leading to the manual exchange from being taken by another subscriber.

Each trunk line, such as LO_1 , extending between the manual exchange MA and the first rural exchange CR may be provided at the point where it leaves the manual exchange optionally with a cabinet interpolated therein and shown diagrammatically in Fig. 12.

Each trunk line has, at the rural exchange, an individual selector (Figs. 8, 9 and 10) which will be hereinafter described and the function of which is, when the telephone operator "sets up" a number (for example by means of a dial) to cause a relay belonging to the subscriber or to the desired connecting line to operate to put this subscriber or this line into connection with the trunk line under consideration.

The equipment of the various trunk lines

such as LO_{14} comprises various relays functioning in a manner similar to those of the subscribers' lines LA , and in particular a relay V corresponding to the relay D , a relay O corresponding to the relay A and a series of groups of relays MN corresponding to the relays C_1, C_2, C_3 . The equipment comprises also means the function of which is, when the line LO_{14} , for example is connected to the local line LL and when the telephone operator is trying to connect up with this line to establish a connection to connect this telephone operator not to the line LO_{14} , but to put her into communication so that she can hear over the line LL .

There is also at each rural exchange a calling line finder (see Fig. 11) common to all the trunk lines leading to the manual exchange, the function of which distributor is to connect up in order of succession the calling stations to one of the free trunk lines leading towards the manual exchange.

This calling line finder is composed of two controlling relays Z_1 and Z_2 and of as many connecting relays Y (Y_1, Y_2, Y_3 , etc. . .) as there are subscribers' stations and trunk lines leading to the next rural exchanges.

The relays Z_1 and Z_2 act on each other, working in succession on a four stroke cycle, the effect of which is to operate the relays Y in succession.

Each rural automatic exchange with its local battery (which can be charged from the manual exchange) is completed by one or more local connecting circuits which comprise five relays E, F, G (see Fig. 7) and W, X (see Fig. 4) and permit the telephone operator to cut off a local conversation and clear the local line at the end of such conversation. It also has as many observation relays H for connection to the local line (see Figs. 6 and 7) as there are trunk lines LO leading from the exchange under consideration to the manual exchange.

All these parts are organized and connected to each other in the manner indicated in the figures of the drawings.

The different rural automatic exchanges connected to a trunk line or in a system of several trunk lines are similar and are organized to the manner of working which will now be described.

The working of the rural exchange according to this invention being rather complex, as is also that of all other automatic exchanges, the description about to be given has been divided into several chapters, namely:

1. The calling up of the manual exchange by a subscriber 24 at CR_1 .
2. The operations carried out by the telephone operator to answer the said subscriber 24, who requires to be connected up to a subscriber 23 at the same exchange CR_1 .

3. The description of the individual selector of the trunk lines leading towards the manual exchange.

4. The connection of the calling subscriber 23 to the local line LL .

5. The connection of the called subscriber 24 to the same line LL , the supervision of the conversation and the ultimate cutting off of the subscribers.

6. The calling up of the manual exchange 75 by a subscriber from a rural exchange not connected directly to the manual exchange, for example by the subscriber at CR_2 .

7. The calling up by the manual exchange 80 of a subscriber at a rural exchange not directly connected to the manual exchange, for example the subscriber 26 at CR_2 .

8. The establishment of a connection between two subscribers at different rural exchanges connected to each other without 85 passing through the manual exchange, for example between 26 at CR_2 and 23 at CR_1 .

9. Connection between two subscribers at 90 rural exchanges connected to each other solely by the manual exchange, for example a subscriber at CR_1 and a subscriber at CR'_1 .

10. The description of the cabinet interpolated between the manual exchange and a rural exchange such as CR_1 .

11. Emergency station permitting a rural 95 exchange to continue to communicate with the manual exchange in the case of damage or breakdown.

12. Recharge of the rural exchange accumulators from the manual exchange. 100

When particularly complex operations have to be carried out we have first given a description or condensed explanation which can be followed by referring to the diagrammatic Figures 14 to 18, these descriptions 105 leaving on one side the details and being intended to serve solely as a guide to enable the detailed description of the same operation to be followed more easily afterwards which, without the above mentioned preliminary 110 condensed explanation, would run the risk of being very confused.

1. The calling up of the manual exchange by a subscriber (24 for example) from CR_1 115

As stated above, before describing in detail the working of the various relays which permit a subscriber to be put into connection with the manual exchange, we think it well to describe succinctly the successive operations which take place and which can be followed by reference to Fig. 14.

It must be understood that this figure, like the others of the same kind, shows only the essential parts necessary to make the general working understood. They bear likewise the same reference letters and figures as the detailed figures.

The subscriber operates his magneto the 130

effect of which is to excite the calling relay D, which is brought into the operative position and is locked in a self holding circuit and operates in its turn a relay B, which provides the current necessary for the working of the calling lines finder. The wire carrying this current is, however, controlled by the relays J and M of all the lines leading to the exchange, so that only if one of these lines is free and, in consequence the relays J and M corresponding thereto are at rest, the line finder receives the current and can be operated.

This selector, as has been stated, comprises a series of relays Y, each corresponding either to a subscriber or to a line leading to a more remote rural exchange. For the moment we shall concern ourselves with the subscribers only. These relays are excited successively one after the other. When one of them is brought into its operative position, it has the effect of connecting the negative pole of the battery to contacts such as 59 (Fig. 14) of the relay D of the corresponding subscriber. These contacts are open when the relay is at rest. When a relay Y is operated this will generally have no effect, but when in its turn, the relay Y₂ of the calling subscriber 24 is operated, it will have the effect of connecting the negative pole of the battery to one end of the relays c₁, c₂, c₃ of the subscriber.

In order that one of these relays may act, it is necessary that its other end shall be connected to the positive pole of the battery, which cannot take place unless the relays J and M of the corresponding trunk line (LO₂ for example) are at rest.

It should be noted also that if several trunk lines are unoccupied at the same time, only one relay c will act, because it is only in the equipment of one of these lines that the necessary positive pole 66 can be found which will be due to the working of the relays J, M, N as will be more fully explained hereinafter.

The relay C₂ having acted will cause the energization of the relay J₂ which, in its turn, excites the calling relay L, the effect of which will be to connect the negative pole to one of the two wires 76 of the line LO₂, this current being sent over LO₂ and lighting up the calling lamp at the manual exchange.

Moreover, C₂ remains in its operative position and connects the subscriber's line with the translator of the line LO₂.

Before proceeding to the detailed explanation of the working of the various parts, we shall indicate in a similar and very abridged manner how the calling line finder works (see Fig. 11).

The relays Z₁ and Z₂ which receive current from the relay B control each other, so that they each pass from the position of rest 65 to the operative position in succession and

vice versa in accordance with the four stroke cycle shown as follows:—

(a) Z ₁ operative-----	Z ₂ at rest
(b) Z ₁ operative-----	Z ₂ operative 70
(c) Z ₁ at rest-----	Z ₂ operative
(d) Z ₁ at rest-----	Z ₂ at rest

The same cycle then commences again.

At the time a, nothing happens.

At the time b, Y₁ is brought into its operative position and is maintained therein, since the succeeding relays are at rest.

At the time c, Y₂ is brought into its operative position, which releases Y₁.

At the time d Y₂ remains in the operative 80 position.

At the first time of the second cycle, the current which previously was sent to Y₁ is interrupted by operated relay Y₂ so that Y₃ is operated and brings Y₂ back to its position 85 of rest and so on.

All the relays Y thus act one after the other. Let us now examine in detail, referring to Figs. 4, 5, 6, 7 and 11, the way in which the operations which have just been 90 described concisely are carried out.

If it be supposed that subscriber Nr. 24 (who, hereinafter will sometimes be called the second subscriber) calls up by operating his magneto, he sends over the line 50, 50' 95 (see Fig. 6) a current into his relay D which operates and is maintained in position over 51, line 301, the contacts of the relays C₁, C₂, C₃, at rest, line 52 (this line being multiplied over all the subscribers of the exchange) and relay B which is caused to operate.

When one of the relays C₁, C₂ or C₃ of the second subscriber is operated, the circuit will be broken and the relays D will return to rest. By being operated the relay B 105 will connect the wire 27 directly to the positive pole 302 and the wire 26 to the line 53. This line 53 has shunts such as 54, which pass through the contacts of the relays J₂, continue through 55 and pass through the 110 contacts of the relays M₂, M'₂ and terminate at the positive pole 56. A similar shunt is provided for each of the lines LO₁, LO₂, LO₃.

If, therefore, one of these lines, LO₂ for example, be free, the relay J₂, and also the relays M₂ and N₂ relating to this line are at rest and the line 53 is connected to a positive pole 56.

Consequently, a positive polarity is placed on the two wires 26 and 27. If a line leading to the exchange were not available, the wire 26 would be disconnected from positive.

By way of example let it be supposed that in the following description, the line LO₁ is occupied and the line LO₂ free.

The current in the wires 26 and 27 will cause the calling line finder shown in Fig. 11 to act in the following manner.

The selector comprises two relays Z₁ and Z₂ and relays Y corresponding to the various 130

subscribers at the rural exchange, Y_1 corresponding to the first subscriber, Y_2 to the second, etc. and also to the lines such as LO_{44} terminating at this exchange CR_1 and coming from other rural exchanges CR_2 .

5 The two relays Z_1 and Z_2 act in succession in the following manner:

10 The current coming from 26 operates Z_1 which is caused to act, Z_2 being at rest, Z_2 is then operated by Z_1 , and which it then cuts out, Z_1 cuts out Z_2 in its turn and the cycle then commences again.

15 We have, therefore, the four following combinations which arise in succession as soon as a current is sent over 26:

- 1. Z_1 operative Z_2 at rest
- 2. Z_1 operative Z_2 operative
- 3. Z_1 at rest Z_2 operative
- 4. Z_1 at rest Z_2 at rest

20 The cycle then commences again.

25 At the time 2 (when Z_1 and Z_2 are operative) the positive polarity coming from 26 is connected, if the other relays Y be at rest, by 57 to the relay Y_1 . If one of these relays (Y_6 for example) were in the operative position, the positive pole would be connected to the next relay Y_7 .

30 If it be supposed that all the relays Y are at rest, the positive pole of 26 will be connected to Y_1 , which will be energized and will be maintained in position by 58 and 27 (if the relay Y_7 were energized, it would be this same relay which would be held by 58 and 35 27).

35 Y_1 being energized, connects to the negative pole by its three armatures the contacts c_1, c_2, c_3 connected to the contacts 59, 60, 61 of the relay D of the first subscriber (Nr. 40 23), this relay D being at rest, however, nothing happens. Y_1 has likewise at 62 connected the relay Y_2 to the line 63.

45 At the third time (when Z_1 is at rest and Z_2 is energized) Y_1 remains attracted.

50 At the fourth time (when Z_1 and Z_2 are at rest) 63 is connected to 26. The relay Y_2 is then energized and cuts off the current in 303 which at 58 maintains Y_1 in position and connects the three contacts 59, 60, 61 of the relay D of the second subscriber Nr. 24 to the negative pole by the contacts c_1, c_2, c_3 .

55 At this moment, as the relay D is energized, the current arriving through C_1, C_2, C_3 from Y_2 energizes, as will be hereinafter described, the relay C_2 corresponding to the free line LO_2 ; the relay C_2 will cut off the current which holds the relay D attracted. As this current energizes the relay B , this latter will be brought to rest and will cut out 26 and 27 which will stop the selector of Fig. 11 and bring all the relays Z and Y to rest. If, however, another subscriber had called up, his relay D would be energized and would likewise keep B energized, and the current flowing in 58 would, therefore, persist and would keep

the last relay $1/p$ attracted which would therefore be in the energized position. As soon as a trunk line is free the selector will begin again to test the different calling lines, the test being effected in their natural order 70 but commencing at $1/p$.

The calling line finder has, therefore, connected the contacts 59, 60, 61 of the relay D of the calling subscriber to the negative pole. We know on the other hand that there is an available line, without which, the line finder receiving no current from 26, would not have acted, and we have also supposed by way of example that the line LO_1 was occupied and the line LO_2 was free. 80

We shall now show that the relay C_1 of the second subscriber will not act and that C_2 on the contrary will act.

To be able to act, C_1 must find a positive pole on the line 64, multiplied over all the relays C_1 . This line is connected by 24 to the individual selector of the line LO_1 and is brought to the resting contact 304 of the relay e of this selector and by 22 (see Fig. 8) to the resting contact 305 of the relay J_1 . 90

If the line LO_1 is occupied by a subscriber of the rural exchange under consideration, namely CR_1 , the relay J_1 will be energized, as we shall see later on, and consequently the preceding circuit is broken. If on the contrary LO_1 is occupied by a subscriber of another rural exchange, as we shall see later on, one of the groups of relays MN of this line LO_1 will be energized. In this case the circuit under consideration, which is continued through 65, will be broken by one of the relays M_1 or M'_1 and cannot be connected to the positive pole 66. 95

Starting from 24, another path is offered to the current through the armatures and contacts of the relays M , but this path is either cut by one of these relays or the current is sent to open contacts. 100

It is important to note here that the bringing of a relay M of the line LO_1 into the operative position or in other words the energizing of it, has the effect of connecting the positive pole 66 to the line 306 and then to the line 67 which leads to the armature 68 of the relay M_2 which plays the same part for the line LO_2 as the corresponding armature of M_1 and, consequently, if the line LO_2 is occupied, extends this positive pole over the line LO_3 and so on. The relay C_1 has not therefore been able to be connected to the positive pole and in consequence remains de-energized. 110

115 On the other hand, the same thing happens in the case of the relay C_3 even if the line LO_3 is free, because the positive pole 66 has not been extended to LO_3 since LO_2 is free. 120

125 The relay C_2 on the contrary, finds by a circuit which is identical (relating to LO_2) the positive pole 66 which has just been trans- 130

ferred to 68 and, therefore, this relay C_2 will act and acts alone.

On coming into the operative position the relay C_2 effects the following operations:

1. It cuts off at 306 the circuits of D and of B which return to rest.

2. It guards the line LO_2 by operating the relay J_2 . Actually, it is held by the negative pole 69 near it and by the positive pole which it finds through the armature 71, the line 72, the relay J_2 (which is energized) 23 (see Figs. 7 and 8) the resting contact 307 of the relay e , the wire 73, 74, the resting contact 308 of the relay F and the positive pole 75.

The relay J_2 being energized, the line LO_2 is guarded, because we have seen, as regards C_1 , that a relay c_n belonging to a subscriber can only act if the relay J_n is at rest.

3. It puts the line 50, 50' of the second subscriber into direct connection with the translator of LO_2 by the contacts 309 and 311 and the line 312, 313.

The calling subscriber 24 therefore becomes connected to the free line LO_2 through the medium of a translator. We shall now see how the telephone operator at the manual exchange is called.

By being energized the relay J_2 has put the relay L_2 into communication, by 314, with the wires 54 and 55 and, therefore, with the positive pole 56. It follows consequently that the relay L_2 is energized and this at 315 puts the wire 76 of the line LO_2 into communication with 28 (see Figs. 7 and 8) and consequently with the negative pole 316 because the relay e is at rest.

There is, therefore, a negative polarity on the wire 76. By referring to Fig. 13, which shows the diagram of the manual exchange, it will be seen that this negative polarity over the wire 76 has the effect of lighting up the calling lamp 77 through the medium of the relay t .

2. Operations carried out by the telephone operator to answer the calling subscriber

We will describe these operations succinctly at first referring to the diagram shown in Fig. 15.

The telephone operator has at her disposal a certain number of double cords equipped with a calling key, a listening key CE_1 , a supervision lamp Sv_1 and an arrangement CN (a dial for example) permitting of the "setting up" of a number for the purpose of calling this or that subscriber.

When the telephone operator sees the calling lamp 77 light up, she inserts the plug in the jack and is then put into communication with the calling subscriber through the medium of the translator. Moreover, the insertion of the plug into the jack has had the effect of lighting up the supervision lamp Sv .

The telephone operator calls the subscriber, who now lifts his receiver off the hook which

connects together his two line wires by way of his receiver. This has the effect of causing the relay K_2 to become energized which short-circuits a condenser 79 placed at the middle point of the translator. The joining of these two wires of the line LO_2 closes the circuit of a relay SP_1 , situated at the manual exchange, which extinguishes the supervision lamp. Being thus warned that the subscriber is on the line, the telephone operator asks him what connection he desires. When he has replied, he replaces his receiver on the hook and the telephone operator "sets up" the number which gives the connection asked for.

We will now describe the same operations in a slightly more detailed manner reference being had to Figs. 4, 5, 6, 7 and 13.

As soon as the telephone operator has seen the calling lamp light up, she inserts her plug into the jack which has the effect of extinguishing the calling lamp and lighting up the supervision lamp through +78, and the sleeve of the jack and plug.

She then operates her calling key which rings the calling subscriber's bell through the medium of the translator of LO_2 .

This subscriber then, and only then, lifts his receiver, or his hand microphone combination, off the switch-hook.

By doing this, he completes the circuit formed by the lines 50, 50'—312, 313 and consequently permits the relay K_2 to act.

This relay K_2 , on energizing, short-circuits at 316, the condenser 79, which establishes connection directly between the two wires of the line LO_2 .

This has the effect, at the manual exchange, of operating the double wound relay SP_1 and extinguishing the supervision lamp Sv . This warns the telephone operator that the subscriber has taken his receiver off the hook and that she can speak to him. She operates the listening key CE_1 and the calling subscriber tells her the number of the subscriber with whom he wishes to be connected.

The telephone operator now proceeds to set up a number for example that of the wanted subscriber so as to put herself into communication with him.

This is done in the following manner.

By inserting her plug in the jack without operating the listening key CE_1 , the telephone operator connects the second wire 318 of the line with the negative pole 319 connected to one of the windings of SP_1 . When the telephone operator operates her listening key she substitutes for the negative pole 319 the negative pole 81 connected to the apparatus CN (a dial or like) which permits of the number required being set up. This apparatus produces, in the line 318, short current interruptions separated by more or less long restorations of the current.

These current impulses operate the individual selector of the line LO_2 , acting directly

on the relay a of this selector (see Fig. 8) which they reach by the following circuit; wire 318, armature 321 of N_2 , wire 322, armature 323 of N'_2 , wire 324, armature of the relay K_2 which has returned to rest, wires 325 and 25 (see Figs. 5 and 8).

3. Description of the individual selector of the trunk lines which lead to the manual exchange

10 A large number of operations are effected by the aid of the individual selector of the line LO_2 , and it has been thought well, before going any further, to explain the working of this apparatus, which is also the same 15 for the lines LO_1 , LO_2 , LO_3 at the exchange CR_1 and for the lines LO_{14} , LO_{15} at the exchange CR_2 . This apparatus has been shown in a purely diagrammatic manner in Fig. 16 and in a more detailed manner in Figs. 20 8, 9 and 10.

It may be divided into three parts each of which is shown in one of the above-mentioned figures.

25 The part shown as Fig. 9 in Fig. 16 comprises a series of contacts 11, 12, 13, etc. . . . each corresponding either to a subscriber at the exchange under consideration, or to lines leading to a more remote rural exchange, or to certain circuits of the rural exchange under consideration, the object of which is to permit of certain operations being carried out such as: the connection of a subscriber to the circuit LL for the purpose of putting two 30 subscribers of the same exchange into communication, breaking the preceding circuit, recharging the accumulators of the rural exchange, etc. . . . which various circuits will be described hereinafter.

40 These contacts are grouped in tens: 11 to 20, 21 to 30 and so on connected to the contacts of S_1 , S_2 , each of which corresponds to one of the groups. To each contact corresponds an armature of the said relay. All the armatures corresponding to the 45 contacts, the unit digit of which is the same, for example 11, 21, 31 etc. . . . are connected together by conductors such as 141.

The object of this arrangement is to connect the contact corresponding to the number 50 formed, at the manual exchange, to the negative pole of the battery at the rural exchange CR_1 , the effect of which is to carry out the operation desired. For example, if the number 55 23 has been set up, at the manual exchange, over the line LO_2 to the exchange CR_1 , the negative pole will be connected to the relay C_2 of the subscriber 23 who will thus be put into communication with the line LO_2 60 in the manner which has been hereinbefore explained.

The working of this part of the selector is as follows:—

At the first operation, the current is sent 65 over that one of the relays S_1 , S_2 , etc. . . .

which corresponds to the tens desired. If for example number 23 is set up the relay S_2 , which corresponds to the number comprised between 21 and 30 will be operated.

At a second operation, the negative pole 70 is connected to the conductor 141 connecting all the armatures corresponding to a number ending in the digit 3, (13, 23, 33, etc. . . .) and of these armatures the armature 23 alone will be in the operative position. Therefore, 75 the contact 23 will be connected to the negative pole.

These two operations are effected by means of the arrangement shown in Fig. 10 and Fig. 16. It is identical with the calling line 80 finder previously described and shown in Fig. 11 except in the following points:

The relays i , j , k etc. . . . corresponding to the relays Y are operated not by the relays Z_1 and Z_2 , which act automatically until the current which operates them is cut off by the relay B , but by the relays c and d of the arrangement shown in Fig. 8 and Fig. 16, which are themselves operated by the interruptions and restorations of the current produced by 90 the dial CN at the manual exchange.

The relays i , j , k are ten in number, and work one after the other and when one of them, the relay K , which is the third one for example, is brought into the operative position, it connects, on the one hand, the relay S_8 to a common wire 99 (terminating at 4 in Fig. 10) and, on the other hand, the common wire 141, which connects those armatures of the relays S , which correspond to the numbers terminating in a three (13, 23, 33), to another common wire 106 (connected to 5 in Fig. 10).

The arrangement which constitutes the 105 third part of the selector is provided for the purpose of: firstly, operating in succession the relays i , j , k , etc. . . . at each interruption and restoration of the current produced by the dial at the manual exchange; secondly, 110 for connecting to a negative pole the wire 99 on the first operation and the wire 106 on the second.

If we compare Figs. 8 and 11 it will be seen that:

The wire 57 of Fig. 11 corresponds to the 115 wire 89 (terminating at 1) of Figure 10.

The wire 63 of Fig. 11 corresponds to the wire 136 (terminating at 2) of Figure 10.

The wire 58 of Fig. 11 corresponds to the 120 wire 91 (terminating at 3) of Fig. 10.

If we refer back to what has been said above concerning the working of the calling line finder (see Fig. 11) it will be seen that it is necessary, in order to operate relays i , j , k etc. . . . in succession to have—

1. the positive pole connected permanently to the wire 91.

2. the positive pole on the wire 89 and the wire 136 disconnected in order to operate a 130 relay of an odd order (i , k , . . .).

3. the positive pole on the wire 136 and the wire 89 disconnected in order to operate a relay of an even order ($j, l \dots$).

The third part of the selector shown in detail in Fig. 8 comprises several relays the functions of which will now be described.

The relay a is operated by the current coming directly from the dial of the manual exchange. It operates the relay b which follows its movement and which for this reason, has been called a repeating relay. As long as the plug is in the jack, these two relays are normally energized, and are brought to the position of rest each time the dial interrupts the current. The relay e , called the guarding relay, is a retarded relay. As soon as the relay a operates, the relay e is energized and is kept in the operative position all the time while the plug is in the jack. The relays c and d serve to connect the wires 89 and 136 alternately to the positive pole +86. It will be seen by simply referring to Fig. 8 that we have: the positive pole 86 on 326 and 136 when d and c are both at rest: the positive pole 86 on 87 and 89 when d is energized whatever be the position of c .

The next relay f is a retarded action relay. When the relay d is energized, the relays f and i are likewise energized and afterwards the relay f remains energized as long as the current which operates it is not cut off for a sufficiently long interval of time. In order to set up a number, 23 for example, the telephone operator inserts her finger into the hole 3 in the dial, turns it until it strikes against the stop and then lets the dial run back. In this movement the dial produces two interruptions separated by a restoration of the current. The interruptions are too short to allow the relay f to release.

The telephone operator then repeats operation by inserting her finger in the hole 3, but this takes sufficient time for the relay f to release. It does not resume its operative position until the return movement of the dial, and again releases when the number has been set up or dialled.

While the relays c and d operate the relays i, j, h in succession, the function of the relay f is first to operate the relays g and h which, at the end of each operation, send out the necessary currents, that is to say, after the formation of the digit 2, they send over the wire 99 (see Fig. 10) the current which operates the relay S_2 by way of the contact established by the relay j , and after the second operation that is after the digit 3 has been sent, they send a current into the wire 106 which, by the contact closed by the relay K , arrives at the terminal 23 (see Figure 9).

The above description of the selector is a summary being in substance diagrammatic like Fig. 16. Its sole object is to furnish data which will serve to make the detailed description about to be given easier to grasp, as the

complication of this latter would be somewhat difficult to follow without this condensed preliminary description.

It will always be supposed, in order to make matters clearer, that the telephone operator wishes to set up or dial the number 23.

As soon as the telephone operator has inserted her plug into the jack of LO_2 , a negative pole (either 319 or 81) as has been stated above, has been connected to the wire 318, and consequently through 25 to the relay a of the selector (see Fig. 8). This relay becomes energized and also energizes the relay b , which will likewise return to rest at the same time as a the movements of which it repeats exactly.

The relay b then connects the negative pole 327 with 328 which causes the relay c to be operated. This latter as soon as it is energized, remains attracted by the pole 329. As has been already stated this relay is a retarded release relay and will remain attracted as long as the plug remains in the jack.

By becoming energized the relay e connects the positive pole 97 to the wire 96. On the other hand the relay c is energized by: the positive pole from the wire 96, 331, contact 332 of d at rest, 333 and the negative pole 327.

To recapitulate: we find that we have relays a, b, e, c energized, relays d, f, g, h at rest, and the selector is ready to receive the impulses which will be transmitted to the relay a by interruptions and restorations of the current caused by CN at the manual exchange (see Fig. 13).

The relay e , on the other hand, has connected a positive polarity over the wire 91 (Fig. 10) by the following circuit: wire 96, 6 (Figs. 8 and 9) 95, armature of S_3 at rest, 94, the armature of S_2 at rest, 93, armature of S_1 at rest, 92, 3 in Figs. 9, 8 and 10, wire 91. The part of the selector shown in Fig. 10 is therefore in a condition to operate.

The telephone operator now dials the number 23 by the help of the calling disc shown diagrammatically at CN (see Fig. 13) and the function of which is to interrupt the continuity between 334 and 335 a certain number of times, and consequently to make the relay a of the individual selector vibrate as many times. The telephone operator first dials the tens digit by inserting her finger into the opening 2 of the movable disc and then turning the disc until it strikes against the stop. When the said disc is released two interruptions of 334—335 are caused in succession, the periods of interruption and restoration of the current being of very brief duration.

At the first interruption the relay a is released, and thus cuts off the negative pole 98 of the relay b which likewise releases. The negative pole 336 is then connected to 337 and this keeps the relay c energized. The relay e owing to its retarded action, remains energized during the duration of the operations

and consequently the positive pole 97 remains permanently connected to the wire 96.

The relay *d* is then energized through 388, the energized relay *c*, 339, the relay *b* at rest and the negative pole 327.

By becoming energized the relay *d* connects the positive pole 86 to 87 (1) of Figs. 8 and 9, wire 89 (Fig. 9).

As has been explained previously in the abridged description of the selector and in the description of the calling line finder, this has the effect of energizing the first relay *i* in Fig. 10, which remains energized owing to the fact that the wire 91 is connected to the positive pole 97 over the circuit above indicated.

In addition, relay *d*, by becoming energized, has energized the relay *f* through 341, 342, the energized relay *d*, 343, the relay *b* at rest, the negative pole 327. The relay *f* is held by the negative pole 344 and thus remains energized for the whole of the duration of the current impulses which are rapidly taking place. This is in consequence of its being a retarded release relay and we shall see hereinafter that a prolonged current causes it to return to rest.

The relay *f* in its energized state operates the relay *g* through the negative pole 345, 346, the relay *h* at rest 347, 348 and the wire 96 connected to the positive pole 97.

The position of the relays in Fig. 8 is now as follows:—

a and *b* at rest. *e* energized. *c* energized. *d* energized. *f* energized and *g* energized. *h* at rest.

The interruption which has just been produced is followed by a restoration of the current the effect of which is to re-energize *a* and *b*; *e* remaining energized. The relay *c* no longer receiving a negative from 336 through 337 releases; the relay *f* remains energized and consequently the relay *d* remains energized since it now receives the negative polarity through 347, *f* energized, 348, *d* energized, 333, *b* energized, negative pole 327. The relay *g* likewise remains energized.

The position of the relays is therefore now: *a*, *b*, *e* energized, *c* at rest, *d*, *f*, *g* energized. *h* at rest.

The second interruption of the current releases *a* and *b*, *d* is cut off from the negative pole 327 and returns to rest, *c* likewise remains at rest; owing to *c* and *d* being at rest, the positive pole 86 is connected up to 349, 326 (2) figs 8 and 10, wire 136 (Fig. 10) and as has been explained above the effect of all this is to operate the relay *j* and to return the relay *i* to rest.

The relays of Fig. 8 therefore occupy the following positions:

a and *b* are at rest, *e* is energized and operative, *c* and *d* are at rest, *f* and *g* are energized and operative, *h* is at rest.

The second restoration of the current brings

back *a* and *b* to the operative position, *c* will be brought back to the operative position by: positive wire 96, 351, 331, 332, the relay *d* at rest, 333, the relay *b* operative and the negative pole 327. *d* remains at rest.

The positions occupied by the relays in Fig. 8 is therefore the following:

a, *b*, *c* and *e* are energized. *d* is at rest. *f* and *g* are energized. *h* is at rest.

We can summarize the operations which have just been carried out in the following table *o* meaning energized or operative and *r* at rest:

Relay	Introduction of the plug.	First interruption.	First restoration.	Second interruption.	Second restoration.	80
<i>a</i>	Operative	<i>r</i>	<i>o</i>	<i>r</i>	<i>o</i>	85
<i>b</i>	Operative	<i>r</i>	<i>o</i>	<i>r</i>	<i>o</i>	
<i>e</i>	Operative	Operative	Operative	Operative	Operative	
<i>c</i>	<i>o</i>	<i>o</i>	<i>r</i>	<i>o</i>	<i>o</i>	
<i>d</i>	<i>r</i>	<i>o</i>	<i>o</i>	<i>r</i>	<i>o</i>	
<i>f</i>	<i>r</i>	<i>o</i>	<i>o</i>	<i>o</i>	<i>o</i>	
<i>g</i>	<i>r</i>	<i>o</i>	<i>o</i>	<i>o</i>	<i>o</i>	
<i>h</i>	Rest	Rest relay <i>i</i> acts	Rest	Rest relay <i>j</i> acts	Rest	90

It will be seen that the positions of the relays *a*, *b*, *c*, *d*, *e* are, on the second restoration of the current, the same as after the insertion of the plug. If therefore instead of making up or dialling the number 23, a higher number be made up or dialled say 63 for example, the interruptions and restorations of the current which would be successively produced would have the same effect and reproduce the same cycle that is to say on interruptions of an odd order *d* would be energized and a relay of an odd order (*i*, *k*, *m* . . . .) in Fig. 10 would be operated.

On interruptions of an even order *c* and *d* would be both at rest and a relay of an even order (*j*, *l*, *n* . . . .) in Fig. 10 would be operated.

The six relays in Fig. 10 are therefore also operated in succession.

Let us return to the example selected of the number 23 to be transmitted.

After the second restoration of the current, the disc stops and the telephone operator inserts her finger into the hole 3 and begins the preceding operation over again, but between the stoppage of the disc and the moment at which it commences to return to its original position, producing as it does so three interruptions of the current in succession, a very much longer time elapses than the duration of the interruptions and restoration of the current which have previously taken place and this will permit the slow relay *f* to release.

Every time the relay *b* is energized, *f* is shortcircuited by 352, the energized relay *f*, 353, the energized relay *b* and the negative pole 336. As this relay is a retarded release relay, it remains operated owing to the brief duration of the periods of restoration of the

70

105

115

120

125

130

current. Now this duration is longer and the relay *f* returns to rest.

The relay *g* is then kept attracted by 117, 116 and 345. On the other hand, the relay *h* is energized, because it is excited by 354 and 355, the energized relay *g*, 356, the relay *f* at rest, the energized relay *a* and the negative pole 98. Immediately it is energized, it remains attracted by the negative pole 358 and 354.

The negative pole 98 moreover is connected not only to the relay *h* but also to (4) in Figs. 8 and 10 and consequently to 99 and 137 and then by the energized relay *j* as has been already explained. It is connected to 359 (9) in Figs. 10 and 9, 138 and the relay *S*₂ which is then energized and is kept in this position by 361 (7) Figs. 9 and 8, the energized relay *h* and the negative pole 103.

By becoming energized the relay *S*₂ breaks the circuit which connected the positive pole to the wire 91 (Fig. 10) over the circuit indicated above, the relay *j* then returns to its position of rest and the apparatus shown in Fig. 10 is returned to its original position. It is now ready to commence to work again, because the wire 91 is going to be connected by (3) Figs. 10 and 8, 361, 104 of the energized relay *h* to the positive pole 75.

The new series of impulses produced by the dial will cause the relays *c* and *d* to act, as previously. At the first interruption *f* will be brought back into its operative position. As *h* is also energized, the relay *g* will be cut off from the negative pole 345, on the other hand by *f* (which is energized) and on the other hand by *h* likewise energized.

Everything will happen therefore as in the first series of operations in which the tens digit of the number asked for was dialled, except that, during the whole of this second operation *g* will be at rest and *h* will be energized.

When the dial stops it will again produce a current of a duration which is sufficiently long to allow the relay *f* to return to rest. This will connect a negative polarity to the wire 106 (Fig. 10) through 106, (5) Figs. 10 and 8, 362, the relay *g* which is at rest, 356, the relay *f* which is at rest, 357 the relay *a* which is energized and the negative pole 98.

The relay *K* in Fig. 10, which corresponds to the Figure 3 having been energized, this negative polarity will be transmitted by the energized relay *K*, (13) Figs. 10 and 9, 141, the energized relay *S*₂ to the terminal 23, as was required.

The relay *h* is now shortcircuited by the negative pole 345, the relay *f* which is at rest, 116, 117, the relay *g* which is at rest, 118, the relay *h* which is energized and which therefore returns to its position of rest.

In conclusion we would point out that if the current passing through the relay *a* is interrupted during a fairly long time the

retarded release relay *e*, shortcircuited through the negative pole 363, the relay *b* at rest, 364, will return to rest and the relays *a*, *b* *c* being at rest, the others will be necessarily brought to rest also. 70

4. Connection of the calling subscriber to the local exchange

To connect the subscriber calling to the local line when he desires to communicate with a subscriber connected to the same exchange as he is himself, the telephone operator dials a conventional number; in practice II has been chosen. Although she can dial numbers by means of her dial, in practice communications between subscribers on the same rural exchange being those which will be the most frequent, it is possible, without however being essential, to set up this number by means of the knob BL (Fig. 13) 85 which the telephone operator has only to push in allowing it afterwards to return to position. This produces two interruptions of the current separated by a sufficiently long time to allow of the return to rest of the relay *f*.

When the telephone operator pushes in the knob BL, the positive pole 83 is connected to the winding of the cut off relay RC through 365. This relay RC becoming energized disconnects the wires 335 from 82 at 84 and connects the positive pole 85 to the relay RR which in its turn is energized and re-establishes the connection of the negative pole 81 and of 82 through 84 of the relay RC which is energized, 366, the energized relay RR. On the other hand this relay RC connects the positive pole 85 to RR which is thus kept attracted.

A certain time being, however, necessary for the relay RR to become energized, it follows that during this period of time the contact between the negative pole 81 and 82 is not re-established and that consequently an interruption of the current is produced of a length which depends solely on the rapidity of working of the relays RR and RC and in no way on the way in which the telephone operator has pushed in the knob BL. 110

When the telephone operator releases the knob BL, the positive pole 85 is connected by 367 to RR which is shortcircuited and returned to rest, cutting off the negative pole 81 from the line 82. On returning to rest, however, RR likewise cuts off the current which keeps RC attracted so that this latter likewise returns to rest which puts the negative pole 81 back again on to the line 82. The current has therefore been interrupted only once and that during the very short period of time which separates the return to rest of the relays RR and RC.

By this operation the telephone operator therefore sends through the medium of the 130

selector, a negative polarity over the terminal 11 of the line L_2 (see Fig. 6 right hand side).

We will first indicate very briefly the various operations which take place, reference being had, either to Fig. 17 in which are shown very diagrammatically only the principal parts which act, or to Figs. 4 to 7 in which all the parts are shown.

When the telephone operator has put a negative polarity on to 11, the relay H_2 becomes energized and remains attracted through the medium of the relay e , which will cause it to return to the position of rest when the telephone operator withdraws the plug from the jack. (It will be seen further on that the relay H can also be kept attracted by one of the relays M , M' , etc. . . .).

The relay H begins by connecting together on the one hand the line 135, 135', terminating at the secondary coil of the translator of LO_2 and, on the other hand, the local line 131. In this way, when the two subscribers are connected to this line, the telephone operator can listen in on the wire.

At the moment under consideration, the calling subscriber denoted by X in Fig. 17, is connected to the line 135, 135' by his relay C_2 . When he has lifted his receiver off the hook he creates a metallic connection between the wires of the local line 134, so that the relay F becomes energized and impresses a negative polarity on the wire 128. The relay K is likewise energized and consequently the negative pole 119 is connected by the relays M and K and C_2 , all of which are energized, to the relay A which, in its turn, becomes energized by being connected up by the negative of the wire 128.

This relay A puts the line of the subscriber into communication with the line 134 and cuts it off from the line 135, 135'. Under these conditions, the relay K returns to the position of rest which lights up the supervision lamp again at the exchange.

5. Connection of the called subscriber to the local exchange

The condensed explanation given below may also be followed with the help of Fig. 7 the subscriber X being this time the called subscriber.

The telephone operator now proceeds to call the wanted subscriber and put him likewise into communication with the local line. For this purpose, she dials the number X of this subscriber (23 for example) and thus sends a negative polarity over the relay C_2 of the subscriber X .

The effect of this operation is to connect the subscriber X (23 for example) to the line LO_2 by exactly the same operations which have been explained in detail in the first chapter and the effect of which was to connect the calling subscriber 24 to the line LO_2 . There is no need to describe them again as the nega-

tive polarity connected by 23 and the wire 142 to the relay C_2 of the subscriber 23 plays exactly the same part as the negative polarity connected previously by the calling line finder to the terminal 60 of the calling subscriber.

When the telephone operator has thus connected up the wanted subscriber 23 to the line LO_2 , she operates the calling key and thus rings the bell of the subscriber who lifts his receiver off the hook. By doing this he operates the relay K_2 and, in the manner as has been explained for the calling subscriber 24, connects the negative polarity 119 to the relay A of the called subscriber 23. Actually the relay H_2 has remained attracted because the relay e remains energized as long as the telephone operator has not withdrawn her plug.

The relay A of the subscriber 23 by becoming energized connects the line of this subscriber to the local line 134. The telephone operator is warned that the subscriber 23 has lifted his receiver off the hook because the working the relay K_2 has at this moment extinguished the supervision lamp. Moreover, relay H_2 being energized the line LO_2 is in shunt with the local line 134, and the telephone operator able to listen in. When she hears that conversation has been commenced, she withdraws her plug from the jack. As has been stated above, this operation releases the relay e of the selector, the operating circuit of the relay H_2 is broken and this relay returns to its position of rest. This line LO_2 is thus freed and can be used for another communication.

If the telephone operator thinks it is advisable to ascertain if the conversation between the subscribers 23 and 24 is finished, or to cut in on the circuit for any reason, it will suffice for her to replace the plug in the jack and to set up on her dial or by the calling knob the number 11. This will have the effect of re-energizing the relay H relating to the trunk line used (which is not necessarily the line LO_2) and the telephone operator will then be in shunt with the local line 134.

If she considers it necessary to cut off the existing conversation, she sets up a conventional number 12 for example, which corresponds to the relay E (see Fig. 7). Negative being connected to this relay, it becomes energized and interrupts, at 129, the circuit, which, by 128, kept the relays A of the two subscribers attracted. The communication is therefore cut off.

If in the course of a local conversation like that which has just been imagined, the telephone operator has to set up, to one of the two subscribers, say No. 23 for example, a communication taking precedence over the local communications, she sets up the number 23, which has the effect, as we have seen, of connecting this subscriber to the secondary

coil of the translator of the trunk line used by the telephone operator. The operator noticing the conversation in progress, she sets up the number 12 in order to cut it off and is thus connected to one subscriber only, i. e. No. 23, the preceding correspondent being cut off and no longer able to hear. In a large rural exchange there may be a number of local lines each having a special number and a series of relays M.

Let us now see what happens when the manual exchange is called up by a subscriber at a rural exchange (CR_2) connected thereto through the medium of the rural exchange CR_1 .

6. *Calling up of the manual exchange by a subscriber on a rural exchange not connected directly to the manual exchange.*

To make matters clear we shall suppose in what follows that we are to consider the case of the connection of a subscriber at the rural exchange CR_2 to the rural exchange CR_1 by the line LO_{14} . We shall suppose likewise that at the moment of calling, the line LO_1 is clear and that connection is made over this line.

At exchange CR_2 , the subscribers are equipped as in CR_1 and that the lines such as LO_{14} leading to CR_1 are equipped exactly as lines LO_1, LO_2 connecting CR_1 to the manual exchange.

Let us first describe the operations very briefly.

When the subscriber, say 26 for example at CR_2 , has operated his magneto, he will connect wire 151 of LO_{14} to a negative pole in the same way as the subscriber 24 of CR_1 , put the wire 76 of LO_2 into connection with a negative pole.

This will have the effect (see Fig. 18) of operating at CR_1 the relays V and B connected in series. Relay B, as we have seen above, operates the calling line finder which, when the relay Y corresponding to the line LO_{14} functions, will impress a negative polarity on one of the armatures of the relay V through 159, the relay M at rest and 158. The relay N will then be operated being connected on the one hand to this negative pole by 164 and on the other hand to the positive pole 66 which, as we have seen previously, can be found on the first, and only the first, free-line.

The relay N becomes energized which energizes the relay M and the two relays hold, negative passing over conductor 177 connected by the relay T at rest, from the negative pole 180.

By becoming energized the relay N puts the line LO_1 into metallic connection with the line LO_{14} .

When the telephone operator inserts her plug into the jack she impresses a negative on the wire 160 and consequently on the wire 171. This has the effect of energizing the

relay P and the relay T, the negative pole 180 being replaced by the negative pole 179 so that the relays N and M remain attracted.

When the telephone operator withdraws her plug, these relays P and T return to rest, but the relay T being a retarded release relay, there elapses between the cutting off of the negative 179 and the restoration of the negative 180 sufficient time for N to return to rest and for everything to revert to the original state.

It will be noted that the individual selector of the line LO_1 (indicated in Fig. 17 by the single relay a) is cut off by the operation of the relay N. Moreover the operation of the relay M has, as has been already stated above, the effect of preventing a subscriber at CR_1 from connecting himself to this line. Everything can therefore take place as if the manual exchange and the rural exchange CR_2 were connected directly and as if CR_1 did not exist at all.

The description given above and Fig. 18 are only for the purpose of enabling the principle of operation to be grasped. Leaving out certain relays the function of which will be dealt with hereinafter, we will now pass on to the detailed explanation of the operation.

The exchange CR_2 is arranged like CR_1 so that, by operating his magneto, the subscriber at CR_2 connects himself to the line LO_{14} , which produces, at the exchange CR_2 , the operation of the relay L associated with LO_{14} and consequently the connection the negative pole to the wire 151 which plays here the part played by the wire 76 when the manual exchange is called up by a subscriber at CR_1 .

In case the call were to come from CR_3 , the relay V (Fig. 4) of CR_2 would be operated as stated above and the negative pole connected at CR_2 to one of the line wires by L would become connected to the wire 151, the effect of which would be to operate the relay V of CR_1 through 152, the relay T at rest, 153, the relay R at rest, 154, the armature 155 and the winding of V.

As soon as this connection is made, the relay V (Fig. 4) becomes excited through the negative pole 151, the wire 152, the armature of T (at rest), the wire 153, the armature of R (at rest), the wire 154, the armature 155, and the winding of V, on through 156, the armature of 157 of M_1 at rest, the wire 158 (Figs. 4 and 5) passing through the armatures and resting contacts of M_2 and M_3 , the wire 159 (Figs. 5 and 7) the winding of the relay B and the positive pole. The relay V is then held, as will be seen from Fig. 4, through the negative pole 367.

The relay B (see Fig. 7) therefore becomes energized as before and sets the calling line finder (Fig. 11) in operation. Fi-

nally when the relay Y corresponding to the line LO_{14} (considered as a subscriber of the exchange CR_1) has acted, the above relay B connects the negative pole to the wires 161, 162, 163 terminating at the armatures of the relay V_1 which play the part above described of the armatures corresponding to the contacts 59, 60 and 61 of the relay D.

Let it be supposed that the trunk line LO_1 is free, the negative from 163 is connected through 154 to the winding of the relay N_1 , thence through 165, the armature of M_1 at rest and 166 to 24 and finally to the positive pole 66, through the connections detailed above in connection with the working of the relays C_1 , C_2 etc.

The relay N_1 becoming energized is connected to the positive pole 167, in series with relay M_1 which is itself, thus energized and caused the positive pole to be transmitted on the line LO_2 as has been previously explained. Circuit LO_1 therefore becomes "busy".

The negative pole on wire 151 is then connected over N_1 (operative) and 368 to the wire 168 of LO_1 , which produces, as has been stated previously, the lighting up of the calling lamp at the manual exchange.

It should be noted that the relay N_1 has produced a metallic connection between the two wires of LO_{14} and the two wires of LO_1 so that the telephone operator is in direct relation with the exchange CR_2 .

As soon as the telephone operator has inserted her plug in the jack the manual negative from exchange is connected to wire 169 of LO_1 and consequently through 161 to the line 171 of LO_{14} , the effect of which is to operate the relay P, through the wire 172. This relay P connects the negative 173 through 174 to the relay S which becomes energized and is kept in this position by the negative 369, thus connecting the negative 175 to the relay T which likewise becomes energized. These operations have the effect of keeping N_1 attracted in another way through 176, 177, the armature of S (operative), 178 and negative 179. N_1 consequently remains attracted even if the connection of the wire 164 with the negative pole is destroyed.

The telephone operator then operates her calling key and the subscriber, whom she is answering lifts his receiver off the hook. The effect of this is, as explained above, to extinguish the supervision lamp. The telephone operator thus warned that the subscriber is on the line can depress the listening key ask him what number he requires and establish the connection. When this connection has been established, the telephone operator withdraws the plug from the jack. The relay P no longer receiving current from the manual exchange returns to rest and shortcircuits S through negative 173, 179 and the armature 278 S. This relay, which is a retarded re-

lease relay, comes to rest after a certain delay and in its turn shortcircuits T through negative 180, the relay T (operative) the wire 181, the armature of S (at rest) and the wire 182. The relay T being likewise a retarded release relay takes a certain time before returning to rest. This time is sufficiently long for the relays M_1 and N_1 to be released by the return to rest of S, which opens the circuit 177, 178 and negative 179 before T comes to rest and reconnects negative 180 to 177.

7. *Calling, by the manual exchange, of a subscriber connected to a rural exchange not directly connected to the manual exchange*

This is the case where the telephone operator desires to call, for example, the subscriber 26 of the exchange CR_2 .

The operation is simple and can be followed easily in Fig. 4.

After having inserted the plug in the jack of a free trunk line connecting the manual exchange to CR_1 for example line 40, the telephone operator sets up the number corresponding to one of the trunk lines connecting CR_1 and CR_2 , for example the number 14 corresponding to LO_{14} .

We have seen that by doing this she connects negative to contact 14 of the selector of LO_1 , shown in Fig. 4 through IX_1 14. This negative pole is connected through 371, the armature of R at rest and 195 to the relay N_1 which will be energized and will remain attracted as explained above.

On becoming energized N_1 directly connects LO_1 and LO_{14} through 368 and 161. The telephone operator is therefore in direct connection with the exchange CR_2 . She can set up the number of the subscriber she wants without having any effect on CR_1 the selector of LO_1 being cut off upon the operation of N_1 . We have seen previously, in considering the selector of LO_2 , that it receives current through 318, 321, 322, 323 and 324, which circuit is broken at 321 or 323 by the energization of one of the relays N.

8. *Establishment of a communication between subscribers of two different exchanges connected to each other without passing through the manual exchange*

As this operation presents certain complications, we shall first describe briefly how it is carried out, reference being made to Fig. 18.

We shall suppose in order to make matters quite clear that it is required to connect subscriber 23 of CR_1 to subscriber 26 of CR_2 and that the lines used for this purpose are LO_1 and LO_{14} .

The telephone operator begins by connecting subscriber 23 to the local line 134 of CR_1 in the manner indicated previously by means of the relay H_1 , which, as will be explained in the detailed description, remains attracted

as long as the plug remains in the jack at the manual exchange.

The telephone operator then calls up the subscriber 26 of CR_2 , as has been previously described. When the subscriber 26 lifts his receiver off the hook he puts the two wires 151 and 171 of the line LO_{14} , into communication through his relay K and consequently the negative pole connected at the exchange to 171 is also connected to 151 and this operates the relay V, which operates and connects the negative pole 186 through the medium of H_1 (energized) to the relay O which in its turn, becomes energized and by doing so:

- 15 1. Is kept excited through the wire 128 which already keeps the relays A of the subscribers at CR_2 attracted (see Fig. 17),
- 16 2. Connects the line LO_{14} to the local line 134,
- 17 3. Cuts off the negative pole 179 from the relay P which returns to rest and consequently brings the relays N to rest, which frees the line LO_{14} ,
- 18 4. Energizes relay R which cuts off the communication between the terminal 14 of the individual selector and the relay N and connects this terminal 14 to the terminal 11. Consequently, if, during the conversation, the telephone operator dials the number 14 with the intention of connecting herself up to the line LO_{14} she will operate the relay H which will enable her to listen in on the local line 134, which will inform her that the line LO_{14} is already occupied.

Let us now examine in detail the operations which take place. The telephone operator begins by putting the subscriber 23 of CR_1 into communication with the local line 134 of this exchange, as has been explained previously, that is through the medium of the relay H_1 .

This relay has remained attracted because it was connected to the negative pole 114 of the selector of LO_1 by 21 (see Fig. 8), 113 and the relay e which is energized.

The telephone operator then calls the subscriber 26 at CR_2 , as has been explained above. By doing so she cuts out the selector 50 of LO_1 and the relay e returns to rest, but at the same time the relay M_1 has become energized whereby N_1 is maintained attracted by the negative pole 372 and the wire 373.

When the subscriber 26 at CR_2 , called by the telephone operator, lifts his receiver off the hook, he causes the relay K of LO_{14} to act and consequently connects up the two line wires 151 and 171 at CR_2 . In consequence of this, the negative pole which was connected at the exchange with 169 and therefore with 171, is likewise connected to 151.

The relays P, S, T are likewise already energized, the others being at rest. As soon as the negative pole is connected to the line 151, the relay U becomes energized in the follow-

ing circuit: 185, the relay T which is energized, 152, and the negative from wire 151. The relay U then energizes the relay O by connecting it to the negative pole 186 through the relay H which is energized, 187, 188, the relay R which is at rest, 191, the relay U which is energized, 192, and finally the winding of O. At the same time U causes R to become energized by negative 373 and 172.

The relay O holds through 194, the wire 193, the wire 128, 129, 130, 132 and negative 133. The relay O will therefore return to rest like the relays A when this circuit is broken by the operation of the relays F or E.

The relay O being energized, directly connects the local line 134 to the line wires 151 and 171 through 374 and 375. Further it cuts off negative 179 from the wire 178, which brings the relays P, S and T back to rest. Finally relay O causes the relay Q to become energized by connecting it through 376 to the positive pole 377.

In consequence hereof, the relays P, S, T having become energized, the relays N and M will return to rest and clear the line LO_1 .

The relay O has put the line LO_{14} into connection with the local line 134, and this relay will return to rest in the same way as the relays A of the subscribers at CR_1 . Finally the relays Q and R have become energized.

These two latter relays have the effect of connecting the wires leading from the numbers 14 (corresponding to the line LO_{14}) of the individual selectors not as previously to the relays N, but to the relays H. The wire 371 leading from IX_1 No. 14 is energized by R (operated) at 196 and by Q (energized) at 197, which is connected to the wire leading from No. 11 of the individual selector corresponding to H_1 .

Consequently if the telephone operator wishes to cut in on the line LO_{14} before the existing conversation is finished, by making up the number 14, she will operate not the relay N but the relay H, the effect of which will be to connect it in shunt with the local line 134 and she will then be able to listen in and ascertain that the line LO_{14} is not free.

9. Communication between two subscribers at rural exchanges connected to each other by the manual exchange only

The establishment of a communication between a subscriber at the rural exchange CR_1 and a subscriber at a rural exchange forming part of another sector (for example the rural exchange CR_1) served by the manual exchange MA presents no difficulty, the connection of the two trunk lines connected respectively to the two rural exchanges (trunk lines to which the two subscribers are to be connected) taking place at the manual exchange by the aid of ordinary double cord.

10. *Description of the cabinet interpolated if necessary between the manual exchange and a rural exchange such as CR₁*

The equipment of the cabinet (see Fig. 12)

5 comprises an indicator z connected into the line wire 318. When the plug is in the jack, a current passes into this wire and operates the indicator which shows that the line is occupied.

10 To obtain communication if the line is free, the magneto 381 which is connected in shunt between the two line wires is operated and the current produced operates the indicator as at the exchange. The telephone operator, 15 thus called, inserts her plug into the jack in order to put herself into communication with the cabinet.

She then operates the calling key 382, which sends a current between the wire 318 20 and earth, and this current drops the indicator AA in the cabinet. The indicator rings the bell 383 and through the armature 384 puts the telephone instrument of the cabinet into shunt between the two conductors 76 and 318. The occupant of the cabinet has only to lift his receiver off the hook for the 25 hook 385, by rising, to cut out the indicator AA and complete the circuit of the microphone 385. The person in the cabinet can 30 then speak to the manual exchange to ask for and obtain the connection which he desires.

The magneto when it is operated, acts on the switch CM which cuts the indicator out 35 of circuit. On the other hand, the indicator z operates a switch C₂ which cuts off the magneto from the wire 318 as long as the line is occupied. The return of the annunciator AA to its place when the cabinet receiver is hung 40 up on the hook again, may be provided for.

11. *Emergency station permitting the rural exchange to communicate with the manual exchange in case of damage*

45 To complete the new arrangement, an emergency call has been provided, organized in such a way that when any one of the rural exchanges is out of order, it can still call up or be called up by the manual exchange. In this case, the calls from the rural exchange are notified at the manual exchange by the emergency indicator AS and the calls from the manually operated exchange will 50 be taken at the rural exchange at a special station called the emergency station indicated by S e c in Figs. 4 and 5. This latter is placed in shunt across the two line wires and is cut off when the relays K and L operate. It follows therefore that every time 55 these two relays are incapable of acting (either on account of faulty condition of the batteries or by reason of failure of the different parts of the operating mechanism to act) 60 the call sent out by the telephone operator 65

(after the usual operations have been carried out) will come directly to the emergency station. In this way the rural exchanges are practically never deprived of a telephone.

12. *Recharging by manual exchange of the accumulators at a rural exchange*

Finally the new system of automatic telephony is arranged to allow of the recharging from a distance of the accumulators at each 75 rural automatic exchange by means of generators placed at the manual exchange. For this purpose there is provided at the manually operated exchange a knob u which permits of the interpolation in the "tip" side 80 of the line wire of a voltmeter in order to measure at the manual exchange at the moment when the calling lamp lights up, by a current from the battery at the rural exchange, the voltage of this battery.

If this voltage is considered to be insufficiently the telephone operator may, after having made the connection she is asked for, charge the battery of the rural exchange under consideration, by dialling a conventional number for example the number 13, assigned to the charging of the batteries. The dialling of this number causes the excitation of the relay v , which becomes energized and remains attracted by 380. This same pole is connected to the winding of x but the other end of this winding being connected to the negative pole of the battery 389 of CR, the current which passes through the relay x is not sufficient to cause it to work. The telephone operator then withdraws the conversation plug from the jack and replaces it by a special plug which connects up to the wire 169 the negative pole of a source of current at a voltage which is higher than that of the battery 389. The relay x then operates, is held by 203 and at 386 and 387 shortcircuits the relay v which returns to rest.

The special recharging plug is of such a shape that when it is introduced into the jack 110 it only comes into contact with the ring contact and consequently with the wire 169 (corresponding for the line LO₁ to the wire 318 of LO₂) the tip contact remaining in its normal position. It follows from this arrangement that even during the charging from a distance of the rural exchange battery, calls arriving from the different rural exchanges connected to the same trunk line are notified at the manual exchange by the relay t . To 115 reply it suffices for the telephone operator to withdraw the charging plug and to replace it by a conversation plug and to proceed as has already been described above. It should be noted that whatever be the number of exchanges connected to the same trunk line (or to several trunk lines) and whatever be 120 the geometrical figure which represents the network formed by the whole of these rural 125 exchanges, the calls sent out by the telephone operator 130

exchanges, the parts at all the exchanges and their working are identical.

The different trunk lines terminating at the manual exchange may be multiplied in front of a number of operators stations the operators being thus afforded the facility of working the system simultaneously, by means of busying arrangement of any known kind which may comprise every trunk line at every rural exchange.

This busying arrangement is arranged to give the operator at the manual exchange an audible signal every time she dials the number, in a rural exchange, of the trunk line leading towards the next rural exchange if the said trunk line is already occupied by another operator at the manual exchange over another trunk line leading from the manual exchange.

20 The new system of relay automatic telephony may comprise any number of automatic rural exchanges placed on any number of trunk lines and the rural exchanges may have any number of subscribers.

25 It should be noted that in the telephonic system according to this invention, a line carries current only when it is occupied. That is if we consider the line LO_1 , the wire 76 is earthed at t at the manual exchange and 30 disconnected in CR_1 . The wire 318 is open by the condenser of AS at the manual exchange, while at CR_1 it is earthed through 321, 322, 323, 324, 317, 325, 25 (see Figs. 5 and 8) and the relay a because it being remembered that 35 the positive poles of the batteries are earthed. For the line LO_{14} at CR_2 , one of its wires is open and the other is earthed, since its equipment is identical with that of LO_1 at CR_1 . For this same line LO_{14} at CR_2 , the wire 151 40 is open and the wire 176 is earthed by the relay P .

45 It will be seen that the example above described and illustrated in the drawings is furnished by way of example and that the relay automatic system of telephony which forms the subject matter of the present invention may undergo all kinds of modifications of details without departing from the spirit of the invention.

50 What I claim is:—

1. In a telephone system of the type including a manual main exchange and several automatic rural exchanges with which subscribers are connected, each of the latter being equipped with local battery telephones having magneto ringing means, and wherein in each rural exchange is connected with the manual exchange by trunk lines, some directly and the others through the intermediary of less remote rural exchanges, the combination in each rural exchange of main trunk lines leading towards the manual exchange, transformers inserted in said lines, the primary and the secondary of which are each

constituted by two windings separated by a condenser; secondary trunk lines leading towards the more remote rural exchanges, and crossing the outer main trunk lines on their outer side opposite the transformers, subscriber's lines crossing the main trunk lines on that side thereof on which the transformers are located; a local line crossing the said subscribers' lines and the said secondary trunk lines; relays responsive, some to the operations of the subscribers, and some to the operations of the manual exchange, and including local communications and communication relays calling relays and observation relays; means responsive to the operations of said relays for connecting the lines crossing each other, and a calling line finder and an individual selector for each main trunk line.

2. In a rural automatic exchange according to claim 1, equipments for the subscriber's lines, each including a local communication relay and means responsive to its operation for connecting the subscriber's line with the local one; the communication relays being of the same number as there are main trunk lines, and the means responsive to the operation of said relays being adapted for connecting the subscriber's line with the corresponding main trunk lines; a calling relay responsive to a call made by the subscriber and means responsive to the operation of said relay for energizing the communication relay of said subscriber's line corresponding to the first disengaged main trunk line.

3. In a rural exchange according to claim 1, equipments for the main trunk lines, each including a guarding relay energized when said trunk line is engaged by a subscriber of said rural exchange, and as many guarding relays as there are secondary trunk lines ending in said rural exchange, and energized when the corresponding main and secondary trunk lines are connected together, and means responsive to the operation of said guarding relays for preventing the corresponding main trunk line, when engaged, from being connected with another line.

4. In a rural automatic exchange according to claim 1, equipments for the subscriber's lines, each including a holding calling relay energized when the subscriber rotates his magneto, means responsive to the operation of said relay for operating the calling line selector, said means including a circuit closed only when all the guarding relays of at least one of the main trunk lines are in inoperative position, means responsive to the operation of said selector for connecting a negative pole with the first end of the winding of all the communication relays belonging to said subscriber's line, and means responsive to the operation of the guarding relays for connecting a positive pole with the second end of the winding of the communication relays belonging to all subscribers' lines and corre-

- sponding to the first disengaged main trunk line.
5. In a rural automatic exchange according to claim 1, a calling line selector including as many selecting relays as there are subscribers' lines and secondary trunk lines, and two relays controlling each other; means responsive to the operation of said two relays for producing four sorts of connections always succeeding each other in the same order; means responsive to the establishment of one of said connections for energizing one of the connecting relays; means for holding said relay in operative position; means responsive to the establishment of a further connection for energizing the following connecting relays; means responsive to the operation of said latter relay for releasing the former one; and means responsive to the action of the connecting relays and of the calling relays of the subscriber's line for connecting a negative pole with one end of the winding of all the communicating relays of the calling subscriber's line.
- 10 6. In a telephone system according to claim 1; means in the automatic rural exchanges, responsive to the operation of the guarding relays, for connecting a negative pole with the first wire of the first disengaged main trunk line; and means in the manual exchange, responsive to the connection of said pole, for lighting a calling lamp.
- 15 7. In a telephone system according to claim 1, a jack in the manual exchange, for each main trunk line, plugs and cords with their equipments including a supervisory lamp, means for lighting said lamp when the operator plugs in a jack; means in the automatic rural office, responsive to the removing of its receiver by a subscriber connected with a main trunk line, for shortcircuiting the condenser inserted in the primary of the transformer of said line; and means in the manual exchange, responsive to said shortcircuiting for extinguishing the supervisory lamp.
- 20 8. In a telephone system according to claim 1, means in the manual exchange responsive to the plugging in of a jack for connecting a negative pole with the second wire of the corresponding main trunk line, a digitized dial, means responsive to the return of said dial in its position after having been digitized, for producing short interruptions of said connection; an individual selector in each rural exchange, for each main trunk line an individual selector including a first group of relays corresponding to the tens of the numbers to be transmitted, ten armatures for each of said relays and each corresponding to the units of the number to be transmitted; a second group of ten relays, and a third group including quick and slow working relays, said slow relays being so adjusted that they remain in position during the return of the digitized dial but are operated while said dial
- 25 9. In a rural exchange according to claim 1, means for connecting with the local line a subscriber's line already connected with a main trunk line, including an observation relay for said main trunk line, means responsive to the operation of the individual selector of said trunk line for energizing said relay when a special number is formed by the dial, means responsive to the operation of the observation relay for connecting in parallel said main trunk line with the local line and energizing the local communication relay of the subscriber's line, means for holding said local communication relay in operating position, means responsive to the operation of said local communication relay for connecting the subscriber's line with the local one, means responsive to the plugging out in the manual exchange for disconnecting the main trunk line and the local line, means responsive to the operation of the individual selector of the trunk line when a special number is formed by the dial, and means responsive to the replacement of the receiver by two subscribers connected both with the local line for releasing the local communication relays of said two subscribers.
- 30 10. In a manual exchange according to claim 1, a jack for each main trunk line, a calling lamp relay connected by the intermediary of a spring of the jack with the first wire of the trunk line, plugs and cords and their equipment, means responsive to the plugging in and to the operation of the listening key for disconnecting the first wire of the trunk line for the calling lamp relay and
- 70 75 80 85 90 95 100 105 110 115 120 125 130

for connecting the second wire with a negative pole, means for forming a special number including a push, means for restoring it into position, means responsive to the operation of said push for actuating two relays controlling each other, and means responsive to the operation of said relays for disconnecting the negative pole from the main trunk line during the time elapsing between the successive operations of the two relays.

11. In a telephone system according to claim 1, means for connecting from the manual exchange a subscriber with a main trunk line, including a digitized dial in the manual exchange permitting the transmission of the number of the subscriber, and a selector in the rural exchange, for each trunk line, and responsive to the operation of the dial for connecting a negative pole with the first end of the communication relay belonging to the equipment of said subscriber's line and corresponding to the calling main trunk line.

12. In a rural exchange according to claim 1, equipments for the secondary trunk lines leading towards the more remote exchanges, each including a local communication relay, a calling relay, and as many communication relays as there are main trunk lines ending in said exchange, a guarding relay in the equipments of said trunk lines, corresponding to each of said communication relays, means responsive to a call coming from the more remote exchange for actuating the calling relay, means responsive to the operation of said relay for actuating the calling line selector, means responsive to the action of said selector for connecting a negative pole with the first end of the windings of all communication relays of said secondary trunk line, and means responsive to the operation of the guarding relays for connecting a positive pole with the second end of all the communication relays corresponding to the first disengaged main trunk line.

13. In a rural exchange according to claim 1, equipments for the secondary trunk lines leading towards the more remote exchanges, each including a local communication relay, a calling relay, and as many communication relays as there are main trunk lines ending in said exchange, a guarding relay in the equipments of said trunk lines, corresponding to each of said communication relays, an individual selector for each main trunk line, means for actuating said selector from the manual exchange, means responsive to the formation on said selector of the number of the secondary trunk line for connecting a negative pole with the first end of the winding of all communication relays of said secondary trunk line, and means responsive to the operation of the guarding relays for connecting a positive pole with the second end of all the communication relays corresponding to the first disengaged main trunk line.

14. In a telephone system according to claim 1, means for connecting from the manual exchange the local line of a rural exchange with a secondary trunk line ending in said rural exchange, an observation relay and an individual selector in the rural exchange for the main trunk line used, means responsive to the operation of said selector for actuating said relay, means for holding said relay in operative position; means responsive to a further operation of the selector for connecting said main trunk line with the secondary trunk line; means in the more remote exchange and manual exchange, for connecting a subscriber in the more remote exchange with said secondary trunk line, means for calling said subscriber from the manual exchange, in the less remote rural exchange, for the secondary trunk line, means responsive to the removal of the receiver of the subscriber of the more remote exchange and means responsive to the operation of said relay for disengaging the main trunk line and for connecting the secondary trunk line with the local one, means responsive to the operation of an individual selector when a special number is formed, and means responsive to the replacement of the receiver by the two subscribers of different rural exchanges thus connected with the local line for releasing said local communication relay.

15. In a rural exchange according to claim 1, an observation relay and an individual selector for each main trunk line, means for connecting a secondary trunk line with the local line, means responsive to said connection for connecting the contacts of all the individual selectors corresponding to the number of said secondary line with the observation relays, means responsive to the connection of a negative pole with one of said contacts for energizing the corresponding observation relay, means responsive to the operation of said observation relay for connecting the corresponding main trunk line in parallel with the local line.

16. In a telephone system according to claim 1, means for grounding at one of their ends the two wires of the main and secondary trunk lines, when they are disengaged.

17. In a telephone system according to claim 1, means for balancing the trunk lines, including, in each rural exchange, at the end of each main trunk line, means responsive to the engagement of said line for connecting its individual selector with the middle point of the primary of the transformer of said line; and, at the end of each secondary trunk line, relays having equal impedances, one being inserted between one wire of said line and the ground and the other being grounded at one of its ends, and means for connecting the other end of said second relay with the other wire of said line and responsive to the engagement of the line.

18. In a telephone system according to claim 1, a cabinet inserted in a main trunk line, one end of which is connected with the manual exchange; a self-restoring drop in said cabinet connected between the ground and one wire of the trunk line, means responsive to the operation of said drop for connecting with the trunk line a local battery telephone with magneto ringing, an indicator, means responsive to the operation of said indicator for disconnecting the magneto when the trunk line is engaged; in the manual exchange, a special drop connected between both wires of the trunk line, a special ringing key, and means responsive to the actuation of said key for connecting an alternative potential supply between the ground and the wire of the trunk line connected with the drop of the cabinet.

19. In a rural exchange according to claim 1, an emergency telephone equipment, means responsive to the operations of certain relays for connecting the same with a main trunk line when said relays are inoperative, and for disconnecting it from said trunk line when at least one of the relays is operative.

20. In a manual exchange according to claim 1, a special key inserted between a voltmeter and the wire of a main trunk line through which passes the current actuating the call lamp, a current supply, a plug adapted to be in contact, when inserted in the jack, with the other wire of the main trunk line, in the rural exchanges, and means for connecting the battery with said wire in order to charge it.

In testimony whereof I have signed my name to this specification.

MICHEL TCHOURBITCH.
